CABINET DRAWER CARRIAGE

Martin Fox, Chicago, Ill., assignor to The Seng Company, a corporation of Illinois

Application September 4, 1944, Serial No. 552,601

4 Claims. (Cl. 45—77)

1

This invention relates to cabinets or desks provided with drawers, and more particularly to an improved carriage for attachment to the back of a drawer to facilitate its movement in or out of the compartment.

It is a common experience that drawers heavily laden with papers, tools, or the like, are difficult to slide in or out of their compartments and also that when a drawer is quite fully extended from its compartment, it tips downwardly so that it is in danger of dropping out. For this reason it is very difficult to see into the extreme back end of the drawer unless it is provided with rather complicated and relatively expensive slide equipment.

The primary object of the present invention is to provide a simple and inexpensive carriage that may be attached to the back of a drawer and make it very easy to slide.

A further object of the invention is to provide an antifriction carriage provided with a bracket having a stop extending upwardly from the back of the drawer, so as to engage a cross-bar at the front of the desk when the drawer is in extended position. The stop prevents the drawer from being accidentally withdrawn completely from the desk, but enables the drawer to be removed by lifting the front end of the drawer when it is extended so that the stop member will be disengaged.

Another object of the invention is to provide an adjusting screw for regulating the distance between the upper and lower rollers, to compensate for wear, and to accommodate the carriage to slight variations in the size of the drawer opening in the desk.

The present application is a continuation in part of my application Serial No. 512,094, filed November 29, 1943, now abandoned.

The invention is illustrated in a preferred embodiment in the accompanying drawing in which—

Figure 1 is a broken longitudinal sectional view of a cabinet and drawer utilizing the invention; Fig. 2, a rear sectional view taken as indicated at line 2—2 in Fig. 1; Fig. 3, a fragmentary plan sectional view taken as indicated at line 3—3 of Fig. 2; Fig. 4, an enlarged fragmentary sectional view of one of the brackets, similar to that shown to the left of Fig. 2; Fig. 5, an enlarged fragmentary sectional view of the rear adjusting mechanism shown in Fig. 1; Fig. 6, a fragmentary side elevational view showing a modified mechanism for adjusting the height of the lower roller; and Fig. 7, a fragmentary

2

sectional view from the rear, showing the bracket illustrated in Fig. 6.

In the embodiment illustrated, a desk or cabinet 8 is provided with the usual drawer 9 having a front panel 10 and a rear panel 11. The cabinet is shown provided with a pair of longitudinally extending top tracks 12 and a pair of parallel bottom tracks 13. The drawer is preferably three or more inches shorter in length than the compartment into which it fits, as is the common practice in desks.

In the drawings, the drawer is shown with similar antifriction carriages at each corner so that it is only necessary to describe one. It will be understood, however, that for light drawers one antifriction carriage may be sufficient, if it is disposed at the center of the rear panel 11, and centrally disposed upper and lower tracks are provided.

20 The antifriction carriage is preferably of the general shape of the right angle triangle bracket 14, having a front flange 15 to enable it to be secured to the back panel of the drawer with suitable screws 16. Preferably the flange 15 extends upwardly above the back of the panel 11, to provide a stop 17, which is disposed so as to contact the cross-bar 18 of the desk, when the drawer is drawn to extended position. However, the drawer may be completely withdrawn from the desk, if desired, by raising the front end of the drawer until the stop 17 tips under the cross-bar 18.

25 A top antifriction roller 19, preferably with ball-bearings, is journalled on the rear extension of the bracket 14, slightly below the stop 17, so as to travel along one of the top tracks 12 of the desk which may be of wood, if desired. The lower antifriction roller 21 is journalled on a slotted arm 22, which is slidably mounted on the bracket 14 by means of headed studs 23. As best shown in Figure 4, the upper end of the arm 22 is bent to provide a finger 24. Preferably a finger 25 is struck from the bracket 14 above the finger 24, and is tapped to receive 30 a bolt 26 provided with a locking nut 27. The lower end of the bolt has a shoulder to abut against the finger 24 and a reduced shank loosely impales the finger. A washer 28 is held in place by an enlarged head 29 on the lower end of the bolt. It will be readily understood that the roller 21 may be raised or lowered to make a proper fit between the tracks 12 and 13 by loosening the lock nut and turning the bolt 26.

35 In the embodiment illustrated in Figures 6 and 7, the lower roller 21 is journalled on a rock arm

30, which is pivotally mounted on a bracket at 31, and may be raised and lowered by loosening a lock nut 32 on a bolt 33, which makes a threaded connection with the member 30, and a swivel connection with the bracket 14, as indicated at 34. If desired, the rock arm 30 may be in the form of a bell crank, so that the bolt 33 would be horizontally disposed and more clearance provided at the lower rear end of the bracket. A recess is formed in the bracket for movably receiving the lower roller.

The foregoing detailed description is given for clearness of understanding only, and no unnecessary limitations should be understood therefrom, for some modifications will be obvious to those skilled in the art.

I claim:

1. An antifriction carriage for desk drawers adapted to be slidably mounted in a drawer compartment, comprising a metal bracket adapted to be secured to the back of a drawer, a top roller journalled in the upper portion of the bracket and having its axis permanently held in one position with relation to the bracket, an arm pivotally mounted in its longitudinally central portion on the lower edge portion of the bracket, a bottom roller rotatably mounted on said arm adjacent one end thereof, a laterally extending ear on the side of the other end of the arm and having a threaded opening, a laterally extending ear on the bottom of the bracket normally spaced from but directly opposite said ear on the arm, an adjusting screw threadably mounted in the arm ear opening and rotatably mounted but held against longitudinal movement in the bracket ear, said bracket having a recess in its lower edge to movably receive the bottom roller, whereby upon rotation of the adjusting screw the axis of the bottom roller will be selectively moved up and down in said recess with relation to the bracket.

2. An antifriction carriage for desk drawers adapted to be slidably mounted in a drawer compartment, comprising a metal bracket adapted to be secured to the back of a drawer, a top roller rotatably mounted in the upper edge portion of the bracket and having its axis permanently held in one position with relation to the bracket, a laterally extending ear fixed to the lower portion of said bracket, an arm pivotally mounted at its mid portion to said bracket, a bottom roller on one end of said arm and a laterally extending ear on the other end thereof, and an adjusting screw threadably mounted in the arm ear and rotatably mounted in the bracket ear, whereby upon rotation of the adjusting screw the axis of the bottom roller will be selectively moved vertically for adjusting the distance between the top and bottom rollers.

3. An antifriction carriage for desk drawers adapted to be slidably mounted in a drawer compartment, comprising a metal bracket adapted to be secured to the back of a drawer, said bracket having an elongated upper edge extending longitudinally rearwardly with relation to a desk

4
drawer to which it is adapted to be secured, a top roller journalled in the rear end of said bracket upper edge and having its axis permanently held in one position with relation to the bracket, a front flange fixed to the front end of said bracket and extending above said bracket upper edge and above the top of the top roller when said bracket upper edge is horizontal, a laterally extending ear fixed on the bottom of said bracket, a movable member pivotally mounted on said bracket for movement in a plane parallel to the plane of the bracket, a bottom roller journalled on one end of said movable member, a laterally extending ear on the other end of said movable member, and an adjusting screw threadably mounted in one of said ears and rotatably mounted in the other ear, whereby upon rotation of the adjusting screw the axis of the bottom roller will be selectively moved up and down with said one end of the movable member.

4. An antifriction carriage for desk drawers adapted to be slidably mounted in a drawer compartment, comprising a metal bracket adapted to be secured to the back of a drawer, said bracket having an elongated upper edge extending longitudinally rearwardly with relation to a desk drawer to which it is adapted to be secured, a top roller journalled in the rear end of said bracket upper edge and having its axis permanently held in one position with relation to the bracket, a laterally extending ear fixed on said bracket, a movable member pivotally mounted on said bracket, the axis of said pivotal mounting passing through the bracket so that the movable member has movement in a plane parallel to the plane of the bracket, a bottom roller journalled on one end of said movable member, a laterally extending ear on the other end of said movable member, and an adjusting screw threadably mounted in one of said ears and rotatably mounted in the other ear, whereby upon rotation of the adjusting screw the axis of the bottom roller will be selectively moved up and down with said one end of the movable member.
